UNITED STATES PATENT OFFICE.

ROBERT COWEN, OF CAMBRIDGE, MASSACHUSETTS, ASSIGNOR TO THE BOSTON WOVEN HOSE AND RUBBER COMPANY, OF BOSTON, MASSACHUSETTS.

DESIGN FOR AN ELASTIC TIRE.

SPECIFICATION forming part of Design No. 28,586, dated May 10, 1898.

Application filed December 4, 1897. Serial No. 660,815. Term of patent 14 years.

To all whom it may concern:

Be it known that I, ROBERT COWEN, a citizen of the United States, residing at Cambridge, in the county of Middlesex and Commonwealth of Massachusetts, have invented and produced a new and original Design for an Elastic Tire, of which the following is a specification.

In the drawings accompanying and forming a part of this specification, Figure 1 is a perspective view of an elastic tire illustrating my design. Fig. 2 is an enlarged perspective view of a section of the tire; and Fig. 3 is a transverse section thereof on the line $x x$, Fig. 1.

The leading feature of my design for an elastic tire consists in a tire having upon its outer circumference or tread-surface two separated groups or a plurality of small parallel ribs extending in the direction of the length of the tire, said groups or bands of ribs being symmetrically located relative to the center of the tread and being separated by a smooth surface or band, the inner circumference of the tire being transversely and continuously convex, forming a smooth surface extending

from the outermost rib of one group to the outermost rib of the other group.

The outer circumference or tread-surface of the tire is shown as provided at each side 30 of its center with two groups or bands $a b$ or a plurality of small parallel ribs extending continuously in the direction of the length of the tire, the said bands or groups of ribs being separated by a smooth band c at the center of the tread, while the inner circumference of the tire is transversely and continuously convex, as at d , extending from the outermost rib of one group to the outermost rib of the other group. 35 40

Having fully described my invention, what I claim is—

The design for an elastic tire substantially as herein shown and described.

In testimony whereof I have signed my name to this specification in the presence of two subscribing witnesses.

ROBERT COWEN.
